UNITED STATES PATENT OFFICE.

FRANZ A. FULLER, OF NEWARK, NEW JERSEY, ASSIGNOR TO THE J. E. MERGOTT CO.,
OF NEWARK, NEW JERSEY, A CORPORATION OF DELAWARE.

BAG FRAME.

Application filed December 22, 1921. Serial No. 524,111.

To all whom it may concern:

Be it known that I, FRANZ A. FULLER, a citizen of the United States, residing in Newark, in the county of Essex and State of New Jersey, have invented certain new and useful Improvements in Bag Frames, of which the following is a specification.

One of the objects of this invention is to provide a metal frame for bags, satchels and the like, of novel and practical construction, embodying improvements in design and arrangements of parts whereby the appearance of the finished article is enhanced and the number of parts reduced, simplified and strengthened.

Another purpose is to produce a bag having combined interiorly with it a separate, smaller bag or purse, it being independently enframed and so arranged as to be accessible only after the main or outer bag is opened, the purse being pivoted to one of the main bag frame elements in such manner as to present a substantially unobstructed opening into it.

A further object is in the provision of means, integral with the frame, for attaching a handle and also for securing the sides of the frame when closed.

These objects, together with others, will become apparent as the description proceeds, and are achieved by the peculiar construction, combination and arrangement of parts hereafter described and shown in the accompanying drawings, forming a component of this disclosure, and in which:

Figure 1 is a top plan view of a bag frame made in conformity with the invention, showing a portion of the bag fabric in engaged position.

Figure 2 is a side elevational view of the same, including the combined purse.

Figure 3 is a partial sectional, partial perspective view, taken substantially on line 3-3 of Figure 2.

Figure 4 is a perspective view of a complete bag, shown open and drawn to a reduced scale.

Figure 5 is a fragmentary sectional view, taken on line 5-5 of Figure 2, showing the manner of attaching the purse.

Figure 6 is a fragmentary side elevational view showing the preferred type of frame construction.

Figure 7 is a perspective view of one of the outer frame casing elements. 55

Figure 8 is a view similar to Figure 6 but showing a modified form of frame construction.

Figure 9 is a perspective view showing in detail the inner frame element used in connection therewith. 60

In the several views, the numerals 15 and 16 respectively represent the outer wall of the main bag and its lining, and 17, in general, designates the purse or interior receptacle. 65

These elements may be of any preferred material, as leather, textile fabrics, etc., etc., common to ordinary hand bag construction, the material being entirely optional. 70

The preferred type of frame structure comprises a pair of relatively thin sheet metal channels 18 and 19, of essentially U shaped cross-section, bent, with their flanges outward, to produce curved corners 20 and 21, from which extend parallel side elements 22 and 23. 75

Both of these frame members are uniform and alike in all respects, and are provided near their ends with perforations 24 for the reception of rivets 25 by which the center members of the frame are eventually attached. 80

These center members consist of two thin metal plates presenting bar elements respectively 26 and 27, having curved corners 28 and 29, blending into projections 30 and 31, all being in the same level plane. 85

The side projections or arms 30 and 31 have parallel inner adjacent edges, but their outer edges are slightly tapered from the curved corners to their ends, and formed on their inner edges, and also along the inner, lower, edges of the bar elements 30 and 31, are a plurality of short integral lugs 32, 90 these lugs, when the frame is assembled, making contact with the bottom of the channel grooves in the frame members 18 and 19, for purposes further on apparent.

Perforations 34, near the ends of the side arms coincide with the perforations 24 when the frames are assembled. 100

Each of the arms and bars also contain a row of spaced perforations 33 closely adjacent their inner edges for the reception of strong thread 35 by which the bag material 105

is stitched in securing its edge to the inner frame members which are disposed within the channels when the bag is assembled, the covering and its lining being disposed over

5 the outer flanges of the channel as shown.

Extending outward from the side elements 30 and 31 are prongs 36 and 37, the same being passed through corresponding open slots formed in hinge leaves 38 and 39 and riveted

10 thereover. The free ends of these hinge leaves are formed into broad, registering, substantially circular plates and perforated to receive tubular rivets or eyelets 40, which act as pivots on which the bag frame opens

15 and closes.

One of the inner frame members has both of its outer corners extended as shown in Figures 2 and 9, the extensions 41 being symmetrical and of any preferred shape, 20 each containing an opening 42 in which is secured the ends of the flexible handle 43, thus eliminating separate fastening devices requiring brazing or riveting.

Also integral with both the bar elements 25 26 and 27 are spring arms 44 and 45 carrying beads 46 and 47, these arms being bent so that the beads or spheres are caused to engage and interlock in the usual manner, but it is to be noted that the carrying arms 30 are part of the structure and not additional attached elements.

The inner bag or purse 17 is provided with any approved type of frame, as 48, having snap catches 49. The hinges 50, at the ends 35 of the frame have as connecting pivots, the shouldered portions of studs 51.

The studs are also reduced in diameter at their outer ends and tightly riveted in the opposite sides of one of the outer frame 40 members, as 23, at points uniformly remote from their ends and so distanced as to permit the purse frame, together with its fastening, to turn freely below the bar elements 18 and 19.

45 Thus due to the purse frame being pivoted at a point off the center of the main bag hinges, when the latter is open, the purse is readily accessible and at the same time much more than the usual space is provided for 50 the entrance of articles or the hand into the main bag as can best be seen in Figure 4.

In the modification, shown in Figures 8 and 9, the structure is varied by extending the ends of the outer channel elements 22' 55 and 23', the flanges being cut away so that the backs of the channels project, each being broadened to overlap as at 54 and 55 and pivotally secured by rivets 56.

In this case, the inner frame members 30' 60 and 31' are cut off so that their ends register with the ends of the channel flanges, and are secured by rivets 25 as before described.

The lugs 32' are used as before to prevent 65 possible abrasion and wear of the thread used in sewing the cover and lining mate-

rial to the inner frame members; the handle clip openings on one of these members is used and also the integrally formed snap fastening means as before described.

70 Prime numerals have been appended to the elements in Figures 8 and 9 that will be seen to correspond with similar elements in the preferred embodiment of the device as previously described.

75 By referring to Figures 2 and 3, the structure will be seen to possess elements of novelty and practicability fully covering the specified objects.

80 As changes in construction could be made within the scope of the invention, it is intended that all matter contained in the foregoing description or shown in the accompanying drawings shall be interpreted as illustrative and not in a limiting sense.

85 Having thus described my invention, what I claim as new and desire to secure by Letters Patent, is:—

90 1. A bag frame comprising a pair of channel members having angular extensions disposed in parallel, plate members disposed within the channeled members, hinge elements connecting the ends of said plate members, the plate and channel members being riveted near their ends, said plate members having perforations for stitching the bag cover thereto, and means formed with 95 said plates adapted to prevent abrasion of the stitches.

99 2. A bag frame comprising a pair of channel members having angular extensions disposed in parallel, plate members disposed within the channeled members, the angular extensions of said plate members having their outer edges tapered inwardly towards their ends, integral rivets extending outwardly from 105 the edges adjacent the ends, hinge leaves secured by said rivets, tubular rivets pivotally connecting the extremities of said hinge leaves, means for attaching the bag material to said plate members, integral lugs extending inwardly from the edges of said plate members adapted to contact with the bottoms of said channels, and means for maintaining said plate and channel members in 110 relative position after assembling.

115 3. A bag frame comprising a pair of U shaped frames having a channel cross-section, flat plate members loosely contained within the channels of said U shaped members, means for attaching bag material to the inner edges of said plate members, hinges connecting the ends of said plate members, the pivotal plane of said hinges being beyond the ends of said channel members, means for uniting the pairs of plate and 120 channel members, and eyes formed integrally at the corners of one of said plate members adapted to receive a handle.

125 4. A bag frame comprising a pair of U shaped frames having a channel cross-sec- 130

tion, flat plate members loosely contained within the channels of said U shaped members, means for attaching bag materials to said plate members, hinges engaging the 5 plate members at their ends, means for securing said plate members within said channel members after assembling, and integral arms formed with said plate members, said arms carrying spheres adapted to engage and 10 lock said frames when said frame elements are in closed relation.

5. A bag frame comprising a pair of channel frames hingedly united at the extremities of their side elements, plate members 15 disposed in each of said channelled frames, means for securing said elements in rigid relation after assembling, means for permitting fastening bag material to said plate members, arms integral with the plate members, 20 said arms being resilient and bent towards each other, and snap engaging means carried by said arms.

6. A bag frame comprising a pair of inner and outer frame members, said outer members being of channel cross-section, said inner members being hingedly engaged, means for 25 positively spacing the edges of said inner members from said channel members, integral eyes on one of said inner members for attaching a handle, and integral spring arms 30 on each of said inner members carrying inter-engaging means.

7. A bag frame comprising a pair of inner and outer frame members, said outer

members being of channel cross-section, said 35 inner members being hingedly engaged, means for positively spacing the edges of said inner members from said channel members, shoulder studs fixed in said channel members to extend in register towards the 40 opposite side, said studs being located in a plane remote from the axis of the frame hinge, and a purse frame having its side elements hingedly connected by the inner 45 ends of said studs.

8. A bag frame comprising a pair of channel frames hingedly united at the extremities of their side elements, plate members disposed in each of said channelled frames, means for securing said elements in 50 rigid relation after assembling, means for permitting fastening bag material to said plate members, arms integral with the plate members, said arms being resilient and bent 55 towards each other, and snap engaging means carried by said arms, shoulder studs fixed in said channel members to extend in register towards the opposite side, said studs being located in a plane remote from the axis of the frame hinge, and a purse frame 60 having its side elements hingedly connected by the inner ends of said studs.

This specification signed and witnessed this 19th day of December, 1921.

FRANZ A. FULLER.
